E. A. NELSON.

TAPPET VALVE MECHANISM FOR INTERNAL COMBUSTION ENGINES.

APPLICATION FILED JULY 19, 1918.

1,388,592.

Patented Aug. 23, 1921.

UNITED STATES PATENT OFFICE.

EMIL A. NELSON, OF DETROIT, MICHIGAN, ASSIGNOR TO E. A. NELSON AUTOMOBILE COMPANY, OF DETROIT, MICHIGAN, A CORPORATION OF DELAWARE.

TAPPET-VALVE MECHANISM FOR INTERNAL-COMBUSTION ENGINES.

1,388,592.

Specification of Letters Patent. Patented Aug. 23, 1921.

Application filed July 19, 1918. Serial No. 245,739.

To all whom it may concern:

Be it known that I, EMIL A. NELSON, a citizen of the United States of America, residing at Detroit, in the county of Wayne 5 and State of Michigan, have invented certain new and useful Improvements in Tappet-Valve Mechanism for Internal-Combustion Engines, of which the following is a specification, reference being had therein to 10 the accompanying drawings.

In Patent No. 1,247,818, granted Nov. 20, 1917, there is disclosed a cylinder head having tappet valves for the inlet and exhaust cylinder ports of an engine, said valves being actuated by a cam shaft, and particular attention has been directed to the lubricating of the valve stems, valve stem caps or sleeve members, and other features. By reference to Figs. 1 and 2, of the patent it will 15 be observed that the caps or sleeve members are interposed between the cam shaft and upper ends of the valve stems, and it is in connection with these caps or sleeve members that I have devised a novel adjustment 20 for the tappet valves. Such adjustment is necessary, from time to time, for various reasons, principally, to compensate for the wear of the cam shaft and the caps or sleeves; the grinding of valve seats, and 25 30 manufacturing inequalities.

The adjusting means which I employ comprises two forms of keys or pins which are disposed between the valve stems and the caps or sleeve members, one form of key or 35 pin having a plurality of facets either of which may be presented to the valve stem by partial rotation or resetting of the key or pin. The other form of key or pin may be considered as having two sets of facets 40 and by reciprocating and rotating the key or pin twice the number of adjustments can be had as with the first mentioned form of key or pin.

My invention will be better understood 45 when reference is had to the drawing and the description thereof, and when describing my invention it is to be noted that while a special form of cylinder head has been shown, it is to be understood that the valve 50 adjusting means is applicable to any engine having cam actuated valve stems.

In the drawings,

Figure 1 is a transverse vertical sectional view of an engine having a tappet valve and

valve adjusting means in accordance with 55 my invention;

Fig. 2 is a horizontal sectional view taken on the line II—II of Fig. 1;

Fig. 3 is a vertical longitudinal sectional view of a portion of the cylinder head; 60

Fig. 4 shows different views of a single key or pin, in plan, and

Fig. 5 is an enlarged horizontal sectional view of a cap or sleeve member provided with a modified form of key or pin. 65

In the drawing, the reference numeral 1 denotes a portion of a cylinder or cylinder block and suitably mounted on the top of the cylinder or cylinder block is a cylinder head 2 having inlet and exhaust ports 3 and 4 adapted 70 to communicate with the cylinder or cylinders of the block. The cylinder head 2 is formed with vertical guides 5 for valve stems 6 of valves 7, said valves controlling the communication of the engine cylinders 75 with the inlet and exhaust ports 3 and 4.

8 denotes a seat at the top of the cylinder head 2 and said seat is formed with a longitudinal lubricant channel or well 9 into which extends the upper end of the valve 80 stem guides 5.

10 denotes a cam shaft housing suitably mounted on the seat 8 of the cylinder head 2, said housing having tubular guideways 11 with the lower ends thereof communicating 85 with the lubricant channel 9 and the upper ends thereof communicating with a cam shaft chamber 12 in the housing 10.

13 denotes a cap or sleeve member slideable in the tubular guideway 11 of the housing 10, said cap having a convex or semi-spherical upper end 14 normally engaged by a cam 15 forming part of the cam shaft 16 journaled in and disposed longitudinally of the chamber 12 of the housing 10. Each cap or sleeve member 13 has its lower end open 90 to communicate with the lubricant channel 9 and provide clearance for the upper end of the valve stem 6, said valve stem having its upper end provided with an annular 100 groove 17 for a split retaining ring 18. The split retaining ring 18 is employed to hold an inverted cup shaped spring abutting member 19 at the upper end of the valve stem 6, said abutment member receiving the 105 upper convolutions of a coiled expansion spring 19 within the cap 13 and disposed about the valve stem 6. The lower convo-

lutions of the expansion spring 20 encircle a thimble 21 made to fit on the upper end of the guide 5 within the lubricant channel 9 and snugly embrace the valve stem 6, said 5 thimble preventing an excessive flow of lubricant from the channel 9 through the guide 5 into the cylinder of the engine. The thimble 21 also supports the lower convolution of the expansion spring 19 and the expansive force of said spring is sufficient to 10 maintain said valve normally closed.

22 denotes a key or pin disposed transversely of the cap or sleeve member 13, said key or pin having its outer end extending 15 into a slot 23 provided therefor in the housing 10, said slot and the chamber 12 being normally closed by a detachable side plate 24 which also serves to hold the pin against longitudinal disengagement from the holes 20 provided therefor in the sleeve. The key or pin 22 is formed with a plurality of facets 25, as best shown in Fig. 4, and the upper end of the valve stem 6 is adapted to snugly engage one of the facets so that 25 through the medium of said pin, the upper end of the cap or sleeve 13 will be normally held in engagement with the pin 15, and consequently the said cam may open the valve 6.

30 Considering the axis of the key or pin 22 the facets 25 are formed in planes at right angle to each other and with the facet planes at different distances from the axis of the key or pin. For instance, one facet 35 may be flush with the side wall of the key, another facet set in two-thousandths of an inch, another set in four-thousandths of an inch, and the remaining facet set in six-thousandths of an inch, it being obvious that 40 all of the facets are different distances from the axis of the key or pin. In consequence of this key or pin construction, it is possible to set the key or pin so as to present a desired facet to the upper end of the valve 45 stem 6 and thereby obtain a desired relation between the valve stem, the cap or sleeve 12 and the cam 15, so that there will be no lost motion and a proper co-action between said elements to insure proper seating of the 50 valve 7 and proper actuation of said valve by the cam shaft. The key or pin permits of the clearance between the cam and cap being regulated and such adjustment can be easily accomplished when the detachable 55 side plate 24 is removed, which removal also gives ready access to the cam chamber, cap, springs and valve stems for adjustment, replacement or repair.

In Fig. 5, there is illustrated a modified 60 form of key or pin 26, as having two sets of facets 27 and 28, either of which may be placed in operative relation to a valve stem by turning the key or pin end for end. Turning end for end and partial rotation of 65 the key or member 26 permits of practically

twice the number of adjustments as is possible with the key or pin 22.

In my former patent previously referred to, it will be noted that the cap or sleeve member had a longitudinal groove with a 70 pin extending therein to prevent the cap or sleeve member from rotating and it was found that such construction had certain disadvantages. Now, with the present construction the pin and groove are eliminated 75 as the outer end of the key 22, extending into the slot 23, prevents rotation of the cap or sleeve member 13 as the key fits snugly in openings in the sleeve with its outer end sliding freely in the slot 23 to prevent rotation of said sleeve, it is impossible for lubricant from the cam chamber 12 to enter the cap except by working downward between the outer surface thereof and its 80 guide 11 into the channel 9. 85

What I claim is:—

1. As a new article of manufacture, a 90 tappet valve adjusting member having facets at different distances from the axis of said member adapted to be engaged by a valve operating member.

2. The combination of a valve stem, means adapted to reciprocate said stem, and adjustable means interposed between said valve stem and its reciprocating means, said 95 adjustable means having a plurality of facets and being adapted to be adjusted to present any one of said facets to said reciprocating means for regulating the movement of said valve stem. 100

3. The combination of a valve stem, a cap inclosing an end of said valve stem, an adjustable key carried by said cap and having a plurality of facets either of which may be 105 engaged by said valve stem, means in said cap maintaining said valve stem normally in engagement with said facets, and means outside of said cap and in engagement therewith adapted to move said valve stem in one direction. 110

4. The combination with a cylinder head having a valve stem extending therethrough, of a housing on said cylinder head and provided with a guideway in which said valve 115 stem extends, a cap reciprocable in the guideway of said housing, a non-rotatable member carried by said cap and having facets, said member being adjustable to bring any one of its facets into operative relation to said stem, means in said cap maintaining said valve stem normally in engagement with said member and adapted to move said valve stem in one direction, and means in said housing engaging said cap and adapted to move said valve stem in the opposite direction. 120

5. The combination with a cylinder head having a valve stem extending therethrough, of a housing on said cylinder head and provided with a tubular guideway and a slot, a 130

- tubular cap slidable in the guideway of said housing, a key in said tubular cap extending into the slot of said housing to prevent rotation of said tubular cap, means in said tubular cap maintaining said valve stem normally in engagement with said key, and means in said housing engaging said cap adapted to move said valve stem in one direction.
6. The combination of a housing, a valve stem extending therein, a reciprocable tubular cap in said housing, and a key in said cap engaged by said valve stem and having an end extending into said housing to prevent rotation of said reciprocable cap.
7. The combination of a housing having a guideway and a slot, a valve stem extending into the guideway, a reciprocable tubular cap for the valve stem in said guideway, and an adjusting member extending transversely of said cap to be engaged by said sleeve and extending into said slot to be removed endwise through the slot.
8. The combination of a housing having an open side, a guideway and a slot in the wall of the guideway at the open side of said housing, a cap reciprocable in the guideway, a cam in the housing to engage the cap, a valve stem extending into the cap, a key extending transversely of the cap in engagement with the valve stem with one end of said key engaging the slot in the housing,
- and a plate to close the open side of the housing and the slot.
9. The combination of a housing having an open side, a guideway and a slot in the wall of the guideway at the open side of said housing, a cap reciprocable in the guideway, a cam in the housing to engage the cap, a valve stem extending into the cap, a member carried by the cap and having facets to be engaged by the stem, said member extending into said slot to prevent rotation of the cap, and means for closing the open side of the housing and preventing removal of said member through said slot.
10. The combination of a valve stem, a cap inclosing an end of the valve stem; a cam to engage and operate the cap, a key extending transversely of the cap and held against rotation thereby, said key being endwise removable and provided with facets at different distances from its longitudinal axis to be brought into operative relation with the valve stem by a removal and repositioning of said key, and means for preventing endwise disengagement of the key from the cap.

In testimony whereof I affix my signature in the presence of two witnesses.

EMIL A. NELSON.
